(57) **CLAIM**

The ornamental design for a television receiver as shown and described.

DESCRIPTION

1. Television receiver

1.1: Perspective

1.2: Front

1.3: Back

1.4: Left

1.5: Right

1.6: Top

1.7: Bottom

1.8: Reference

1.9: Reference

1.10: Reference

1.11: Reference

The claimed design is a television receiver in which a display unit and case are integrated into one body; reproduction 1.8 is a reference view showing the open state; reproductions 1.9 and 1.10 are reference views showing the state of use when the display unit is tilted up, and reproduction 1.11 is a reference view showing the state of use with a stand; the broken lines indicate portions of the article that form no part of the claimed design; the broken lines shown in reproductions 1.8 to 1.11 illustrate environmental structure and form no part of the claimed design.
